UNITED STATES PATENT OFFICE.

JAMES F. CUNNINGHAM, OF NEW YORK, N. Y., ASSIGNOR TO THE E. P. GLEASON MANUFACTURING COMPANY, OF SAME PLACE.

TAPER SLIDE OR HOLDER FOR GAS-LIGHTING TORCHES.

SPECIFICATION forming part of Letters Patent No. 380,094, dated March 27, 1888.

Application filed October 3, 1887. Serial No. 251,355. (No model.)

To all whom it may concern:

Be it known that I, JAMES F. CUNNINGHAM, a citizen of the United States of America, and a resident of the city of New York, in the county 5 and State of New York, have invented a certain new and useful Improvement in Taper Slides or Holders for Gas-Lighting Torches, of which the following is a specification.

This invention relates to an improvement in 10 gas-lighting torches such as described in the Letters Patent of E. P. Gleason, dated June 24, 1873, and No. 140,191, and in Letters Patent of J. W. Houchin, dated February 27, 1883, and No. 273,085; and it consists of a new and novel 15 construction of the sliding wax-taper holder, which is hereinafter fully described and shown. Said taper-holder heretofore was constructed to contract and clamp the wax taper to hold sufficiently by inserting it in the wax-taper guide- 20 tube over it. In consequence said holder had to slide tightly and not readily and very inconveniently in the guide-tube. Said holder has also been constructed with jaws grasping the taper's end when inserted in said tube, 25 which has frequently caused the jaws to cut the taper and separate and bite it off, and said holder has been constructed without a guide-stop to determine the length of the taper end to be engaged by the holder.

30 Therefore, the object of this invention is to provide and construct the holder not to pinch but slide readily in its guide-tube and firmly hold the taper end without cutting it, and that an equal only requisite portion of each taper end 35 be engaged and wasted by the holder; and the object of the invention is also to construct the taper-holder in a manner as to require the least quantity of metal and labor, so that the holder is produced at a more moderate expense than 40 those heretofore in use.

In the drawings hereto annexed, Figure 1 represents a sectional elevation of the upper portion of the torch-holder with a sliding wax-taper holder constructed according to my invention. Fig. 2 is a side elevation of the sliding taper-holder detached and shown on a larger scale than before. Fig. 3 is an end view of the same. Fig. 4 is a vertical section of the same through its portion engaged by the taper 45 end, the line of section being indicated by the

dotted line *a b* in Fig. 2. Fig. 5 is a horizontal section of the same, the line of section indicated by the dotted line *c d* in Fig. 2. Fig. 6 is a face view of the laid-out flat blank or pattern of sheet metal and with an outline to correspond with the said desired and dimensioned taper-holder. Fig. 7 is a diagram showing the relative positions of the blanks as cut from the sheet of metal, the outlines of the blanks shown in dotted lines.

A, Fig. 1, represents the key portion of the torch, and B the wax-taper tube of the same, which latter has the usual longitudinal slot, C, in which the taper-holder D slides. The portion E of the holder is contracted to slide readily in the slot C of the tube B, and F represents the handle portion of the holder, which is partly cylindrical in form and projects laterally from the contracted portion E upon the exterior of the guide-tube, thus forming a handle by which the taper-holder can be raised or lowered by the operator.

The portion G of the holder serves to engage the taper's end. It joints the portion E, and projects inwardly into the tube B, and is made 75 to slide very readily in said tube. Said portion G is formed of the ends I and J of the sheet-metal blanks. Said ends do not quite meet opposite one another, but allow a small space to remain between them. Each is bent in semicircular 80 form to follow the interior bore of the tube B, and they move easily therein. The end I is of equal height with the portions E and F; but the end J extends considerably above, as shown. In the upper extremity of said end J is cut a 85 taper-notch, K, forming two opposite points at the extreme ends. The portion in which the notch K is made is bent downward and made circular in form to conform in shape to the interior of the tube B. The top portion of the 90 end I has a portion forming a lip, L, cut and bent from it laterally to extend inwardly, as shown. The lip L serves as a stop to prevent the extreme end of the taper being placed beyond its required engagement with the holder, and with said end against said lip L the taper 95 is pressed to seat along the inside of the end J and is pressed into the notch K. The holder is thereafter inserted with the taper into the top end of the tube B, and as the holder is slid 100

into the guide-tube the taper is carried with it, and it can be moved in and out of the guide-tube by operating the holder. In the tapered notch K the taper is solidly held to the holder without cutting to damage the taper, and the holder can slide very readily up or down in the tube B.

In constructing the holder (which is preferably composed of one piece of sheet brass, copper, or other suitable metal) a flat blank is cut from the sheet of metal by means of a suitable die and punch, (not shown,) which are preferably of such shape and dimensions as to cut a blank of the shape shown in Fig. 6. After the blank is cut out with the notch K and cut in for the lip L the blank is turned over a proper-shaped mandrel to bring its ends J and I opposite, and with a proper die pressing or closing the blank against and upon the mandrel, forming the nearly-cylindrical portion F, the neck portion E, and the portion G. Said mandrel has a notch, into which the lip L is bent laterally, and has an upward projection with a rounded end opposite the end J, over which the points at each side of the notch K are closely bent. By this means the holder is completed.

The above mode of bending the blank to its

shape may be varied to suit the convenience of the tools.

From the sheet of metal the blanks are punched or cut, and the sheet is fed to the punch from blank to blank relative to each other, as shown in dotted lines in Fig. 7, from which it will be observed that a small waste of metal is produced on account of the rear outline of the blank meshing with the forward outline of the next.

What I claim as my invention, and desire to secure by Letters Patent, is—

The herein-described taper-holder for use in gas-lighting torches, consisting, essentially, of a handle portion, a taper-engaging portion connected with the handle portion by a neck or reduced portion, an arm extending upwardly from the taper-engaging portion and provided with a notch in its upper end, and a laterally inwardly-extending lip located below said notch, substantially as described.

In testimony that I claim the foregoing as my invention I have signed my name in presence of two witnesses.

JAMES F. CUNNINGHAM.
